PACKAGE CONSTRUCTION

Preston Farley, 2328 Lincolnwood Drive, Evanston, Ill.
Filed Mar. 14, 1960, Ser. No. 14,912
4 Claims. (Cl. 229—62)

This invention relates to a package construction and more particularly to a package suitable for mailing and having a pliable thermoplastic bag section and an addressing label heat-sealed thereto.

Various packages of this general type have heretofore been provided which, because of their design, are incapable of inexpensively packaging a wide variety of articles, such as candy, metal fasteners, or the like, and at the same time provide a suitable addressing label which is fused to such bag section. Furthermore, such prior packages do not have the label affixed to the bag section simultaneously with the sealing of the bag open end and forming a part of such seal but, instead, require separate steps which complicate fabrication of the package. A further shortcoming which oftentimes besets such prior packages is the inability of the package to withstand abusive handling and at the same time protect the accommodated articles against dirt and moisture.

Thus, it is one of the objects of this invention to provide a package which is capable of providing protection for its contents against dirt and moisture, is strong, durable, attractive and lightweight in construction, and is suitable for sending through the mails.

It is a further object of this invention to provide a package which has a pliable thermoplastic bag section and an addressing label affixed thereto by heat seal, whereby said label is reinforced by a portion of such bag section.

It is a still further object of this invention to provide a method of forming a package suitable for mailing and having a pliable thermoplastic bag section and an addressing label whereby the latter forms a part of the heat seal applied to effect closing of the filling end of the bag section.

It is a still further object of this invention to provide a package which is easy to handle, is capable of withstanding abusive treatment, may be readily grouped with other similar packages for bulk shipping or storage, is not subject to deterioration, and will not adversely affect the goods being accommodated.

Further and additional objects will appear from the description, accompanying drawing and appended claims.

In accordance with one embodiment of this invention, a mailing package is provided which comprises an article-accommodating bag section formed of a pliable thermoplastic material and an addressing label affixed to one end of said bag section. The label is disposed in straddling relation with respect to the bag section filling end and is provided with segments which overlie the opposite surfaces of said bag section adjacent said end. The label segments are affixed to the bag section surfaces by the application of heat which also effects a heat-seal for closing the bag section filling end.

For a more complete understanding of the invention, reference should be made to the drawing, wherein:

FIGURE 1 is a perspective view of the improved package ready for mailing;

FIG. 2 is an enlarged fragmentary sectional view taken along line 2—2 of FIG. 1; and

FIG. 3 is a perspective view similar to FIG. 1 at a reduced scale, but showing the bag section and label in exploded relation prior to said label being affixed thereto.

Referring now to the drawings and more particularly to FIG. 1, a package 10 is shown which is adapted for accommodating one or more articles which vary widely in size and shape (i.e., hard candy, powdered confections,

2

metal fasteners, etc.). The package 10 is of such construction that, if desired, it may be readily sent through the mails or it may be grouped with other similar packages for bulk shipping or storage.

As shown in the drawings, package 10 comprises a thermoplastic bag section 12 and an addressing label 13 formed of fibrous material which is adapted to be affixed to the upper, or filling, end of the bag section. The bag section 12 is preferably formed from an extruded sleeve of pliable, relatively heavy-gauge thermoplastic material (i.e., polyethylene), and is adapted to have the lower end 14 thereof closed by a heat seal to form the bottom of the bag section. The upper edge 15 of the bag section is initially open, as shown in dotted lines in FIG. 3, to permit ready filling thereof with the desired articles 11 to be packaged. The size and shape of the bag section may be readily varied from that shown and will be determined to a large extent by the configuration of the article or articles to be accommodated thereby. Furthermore, because of the pliable character of the bag-forming material, the bag section is capable of being readily deformed by the accommodated goods and facilitates manual grasping of the package.

Subsequent to filling of the bag section, the opposite portions thereof adjacent the upper edge 15 are brought into abutting face-to-face relation, as shown in FIG. 3, whereupon the label 13, which is folded along a median line, is brought into straddling relationship therewith. The label 13, by reason of the fold, has front and back segments 16 and 17, respectively, which are adapted to partially overlie the exposed front and back surfaces of the bag section. Subsequent to the straddling of end 15 by label 13, portions 16a and 17a of the front and back label segments are clamped between a heating element 35 which simultaneously imparts a predetermined high temperature thereto which effects fusing of the label segments to the bag section and fusing of the abutting back and front side portions of the bag section. Upon release of the heating element the upper end of the bag section is 40 heat-seal closed.

It will be noted that the upper end of the bag section in the illustrated embodiment, extends to the fold-line of the label; however, if desired, the upper end may be shortened with respect thereto. In the illustrated embodiment the sandwiched upper end portion of the bag section serves to reinforce the label. Furthermore, if desired, all of the end portion of the bag section straddled by the label may be fused thereto rather than just a portion thereof as shown. The exposed surfaces of the label segments 16 and 17 may be printed with an appealing greeting or various areas thereof, A, B, C, D, and E, delimited by printed lines. Such areas enable the sender to add a personal greeting to the package, as well as the address of the recipient and the proper postage.

While the label is illustrated as being folded along its median line and in straddling relation with the bag section, it is to be understood, of course, that the label could be varied in size and shape and fused to only one surface of the bag section.

While the bag section 12 has heretofore been described as being preferably formed from an extruded sleeve of polyethylene material, its construction is not to be so limited, as it may be formed from a single sheet of pliable thermoplastic material having its opposite sides folded so as to overlap one another and heat-sealed.

Once the upper and lower ends of the bag section are closed by heat sealing, the contents thereof are protected from dirt and moisture. If desired, the bag section might be filled from the bottom edge 14, in which case the label would have been previously affixed to end 15.

Thus, it will be seen that an improved mailing package has been provided which is of simple, durable and attrac-

itive construction, and is capable of accommodating articles varying widely in size and shape. Furthermore, the package has the addressing label thereof heat-sealed to the package bag section and thus separation of the label from the bag section is avoided.

While several embodiments of this invention have heretofore been disclosed, it will be understood, of course, that the invention is not to be limited thereto, since additional modifications may be made, and it is contemplated, therefore, by the appended claims, to cover any such modifications as fall within the true spirit and scope of this invention.

I claim:

1. A package suitable for mailing comprising a bag section formed of a pliable thermoplastic material and provided with an upper open end portion for filling and adapted to be closed by heat sealing, said heat seal being spaced from the top of said upper open end portion, and an addressing label overlying at least one face of said bag section open end between said heat seal and the top of said upper open end portion and being affixed thereto by the heat applied to said open end to effect heat sealing thereof.

2. A package suitable for mailing comprising a bag section formed of a pliable thermoplastic material, said bag section having front and back sides interconnected along their side and bottom edge portions and their corresponding upper edge portions delimiting an open end for filling, said open end being adapted to be closed by heat sealing the portions of said front and back sides adjacent said open end, the latter heat seal being spaced from the top of said open end; and an addressing label overlying the portion of at least said front side between the top of said open end and the heat seal effecting closing of said open end, said label being affixed thereto by the heat applied to said front and back sides to effect heat sealing of said open end.

3. A package suitable for mailing comprising a bag section formed of a pliable thermoplastic material, said bag section having front and back sides peripherally inter-

connected to form closed side and bottom portions and an open upper end portion for filling said bag section, said open upper end portion adapted to be closed by heat sealing the portions of said front and back sides a distance spaced from the top of said upper end portion; and an addressing label folded over to effect straddling of said bag section upper end portion and the heat sealed part thereof, said label having segments thereof sandwiching therebetween the portions of said front and back sides intermediate the top of said upper end portion and said heat sealed part thereof, said label segments being affixed by heat sealing to said bag section front and back sides by the heat applied to effect closing of said upper end portion.

5 4. A method of forming a package suitable for mailing from a sleeve of pliable thermoplastic material open at opposite ends, applying heat to one end of said cylinder to effect a heat seal and closing thereof and effecting formation of a bag with an opening for filling at the second end, closing said second end subsequent to filling of said bag by bringing opposite surface portions delimiting said opening into face-to-face contact, placing a foldable addressing label in straddling relation with said closed second end, with segments of said label overlying opposite exposed surface portions of said bag adjacent said second end whereby said opposite surface portions of said bag are sandwiched between said label segments, and applying heat to the end limits of said label segments whereby said label segment end limits are fused to the overlain bag portions and the latter are fused together at a distance spaced from the fold of said label and the second end of said bag section.
